UNITED STATES PATENT OFFICE.

CUSTER LEVI THYDEAN, OF BIGFORK, MINNESOTA.

MOTOR-SLED.

1,115,617.

Specification of Letters Patent.

Patented Nov. 3, 1914.

Application filed March 16, 1914. Serial No. 824,969.

To all whom it may concern:

Be it known that I, CUSTER LEVI THYDEAN, a citizen of the United States, residing at Bigfork, in the county of Itasca and State of Minnesota, have invented a new and useful Motor-Sled; and I do hereby declare the following to be a full, clear, and exact description of the invention, such as will enable others skilled in the art to which it applies to make and use the same.

The aim of this invention is to provide an improved motor propelled sled having means to hold the motor against operation, until the operator is kneeling or otherwise on the sled, then the holding means may be released by the foot of the operator, which in turn will release the motor, which will impart motion to the sled.

In practical fields the details of construction may necessitate alterations, falling within the scope of what is claimed.

The invention comprises further features and combination of parts, as hereinafter set forth, shown in the drawings and claimed.

In the drawings:—Figure 1 is a view in perspective showing a portion of the sled broken away illustrating the motor propelled mechanism and the holding means therefor. Fig. 2 is a longitudinal sectional view. Fig. 3 is a transverse sectional view on line 3—3 of Fig. 2.

Referring more especially to the drawings, 1 designates the sled, which may be of any suitable construction or configuration. 35 Journalled in bearings 2 of the sides or runners 3 of the sled are shafts or axles 4 and 5, with which the wheels 6 and 7 are rotatable. One end of the axle 4 is provided with a rectangular or square pintle 8 to receive a key 9, for rotating the axle 4, in order to wind the main spring 10, one end of which is connected at 11 to the axle, while the other end is connected to a pin 12 of one of the sides or runners of the sled. Projecting radially 45 from the axle 4 is a double blade arm 13, which is constructed with a sleeve 14 riveted or otherwise secured on the axle 4. Projecting downwardly from the under face of the top 15 of the sled is a spring arm blade 16, 50 the angle end 17, being fixed to the top as at 18. This spring arm blade normally lies in the path of the arm 13, to prevent the axle or shaft 4 from revolving by the action of

the main spring 10. Secured to the spring blade 16 as shown at 19 is a rod 20, the rear portion of which is supported in a U-shaped staple or strap 21, and terminating in an upwardly extending toe-piece 22.

To allow the sled to be propelled forward, the operator kneels, or otherwise conveniently arranges himself on the sled, and in such wise as to permit the toe or the shoe to engage the toe or foot piece 22, then by pushing the toe piece of the rod 20 rearwardly, thereby throwing the spring arm 65 from the path of the blade arm of the axle or shaft 4, the main spring will be allowed to unwind, thereby imparting motion to the axle or shaft 4 and its wheels, which will cause the sled to move forwardly.

The invention having been set forth, what is claimed as new and useful is:—

1. A motor propelled sled comprising runners, axles journaled in bearings of the runners and including wheels, one of the axles 75 constituting an operating shaft, a motor carried by the operating shaft, a sleeve fixed to the operating shaft and provided with a reinforced double-bladed arm, means on the sled to engage said arm to hold the motor 80 against operation, and a device manually actuated to actuate the means to release said arm.

2. A motor propelled sled comprising runners, axles journaled in bearings of the runners and including wheels, one of the axles constituting an operating shaft, a motor carried by the operating shaft, a sleeve fixed to the operating shaft and provided with a reinforced double-bladed arm, a spring arm 90 upon the bottom of the sled arranged in the path of the arm of the operating shaft, a rod secured to the spring arm and extending rearwardly terminating in a foot piece, whereby the rod may be pushed rearwardly 95 to move the spring arm from the path of the arm of the operating shaft, thereby releasing the motor, and a bearing on the sled for the rod.

In testimony whereof I have signed my 100 name to this specification in the presence of two subscribing witnesses.

CUSTER LEVI THYDEAN.
